UNITED STATES PATENT OFFICE.

WILLIAM H. STOREY, OF LEICESTER, ENGLAND.

TYPE-COMPOSING STICK.

Application filed September 4, 1924. Serial No. 735,746.

To all whom it may concern:

Be it known that I, WILLIAM HENRY STOREY, a British subject, residing at 30 Mere Road, Leicester, England, Great Britain, have invented new and useful Improvements in Type-Composing Sticks, of which the following is a specification.

The present invention relates to improvements in type composing sticks, more particularly for use with type used with Roneo-type or like printing machines.

In composing sticks as at present constructed the locking device for the types has been so devised that it is possible for the operator accidentally to release the spring which retains the type in the stick with the result that types may fall out of the stick, with consequent loss of time in composing.

Or, where manually operated type retaining devices are employed, such as clips, which are required to be moved across the path of the types, there is the possibility that such devices may accidentally be released or alternatively the operator may fail to place the retainers in locking position so that similar disabilities are met with.

Furthermore, it is to be borne in mind that in previously known forms of type retaining devices one end of the fork or stick is always open to receive type, and consequently should the compositor tip the fork so that the composing end of the stick is tilted in a downward direction the types will drop out of the stick.

Now the object of the present invention is to eliminate manually operated type retaining devices and construct type retaining means which lock and release the types automatically and so overcome any possibility of types falling out of the stick.

The invention consists in the use of balls one at each end of the fork the said balls rolling in inclined races, one at each end of the stick and the inclines being oppositely opposed.

According to the invention the composing stick may be formed in any well known manner. For instance it may be of tubular construction there being provided a central slot extending the whole length of the tube.

The composing end of the stick is angled off in such a manner that prongs are formed to engage the channels in the type and so lift them out of the composing fount, while the other end of the stick is also fashioned

with prongs for setting up the type on the forme.

The inclined races may be formed by cutting out and bending inwards portions of the tube. The balls may either be placed in the tube prior to the cutting and bending operations, or they may be inserted in the fork by forcing them past the extremities of the bent pieces.

Alternatively the inclined races may be constructed as separate elements and fixed in the tube as by way of rivets, soldering or like means. Stops are provided at the inward ends of the inclined races to limit the movements of the balls and these stops are so formed as to prevent the balls fouling the type when each ball is at the bottom of the inclined race. For example the stops are provided with curved hoods so that the balls nest therein.

The way and manner in which the invention is carried out will now be fully described, reference being had to the accompanying drawings, whereon:

Fig. 1 is a plan view of one type of composing stick to which the invention is applied.

Fig. 2 is a side view of Fig. 1.

Fig. 3 is a side view, in section.

Fig. 4 is a cross section taken on the line A—B of Fig. 3.

Fig. 5 is a detail view.

Fig. 6 is a part sectional view of the composing end of the stick, tilted so that the ball intercepts the type.

On the drawings 10 represents the composing end of the stick while 10^a represents the end for setting up the type of the forme. The composing stick is shown as being of tubular form there being provided a central slot 11 extending throughout the length of the tube. The composing end 10 is angled off as at 12 so that prongs 13 are formed which prongs engage the channels 14 of the types 15 and so lift them out of the fount and retain them in the central slot or channel 11. The other end of the stick 10^a is also fashioned with prongs 16 for setting up the type on the forme.

The inclined races 17 are shown on the drawings as separate elements secured to the stick, but these may be formed by cutting out and bending inwardly portions of the tube.

In these races 17 are placed the balls 18

and stops 19 are provided at the inward ends of the inclined races 17 to limit the movements of the balls, and these stops are preferably provided with curved heads or hoods 20 so that the balls 18 nest therein, when they are in their normal or lowest position in the races 17.

The stick is provided with the usual thumb or finger piece 21.

10. From the drawings it will be seen that the stops 19 with the hoods 20 are formed in the nature of rivets and are passed through perforations in the races and in the composing stick, and by this means secure the races and the stops to the stick. It is obvious, however, that the stops may be formed by cut out portions from the races 17 and be bent on one side or the other to form curved hoods for the balls.

20. When the stick is being used for composing it is held at an angle the composing end 10 pointing upwardly and the tips of the prongs 13 engage the channels 14 of the type 15 to extract one type at a time from an inclined fount. The stick being held at an angle it follows that the ball 18 at the composing end 10 of the stick is nesting under the hood 20 of the stop 19 while the ball 18 at the other end or setting up end of the stick 10a, has fallen, by gravity, into the path of the type and acts as a retaining device for the types collected into the stick. Should the compositor inadvertently tilt the stick so that the composing end 10 is lowered the ball at that end of the stick will roll along the race 17 into the path of the type and automatically prevent the types from falling out of the stick.

After composing a line of type, the stick 40 is held in a horizontal plane the prongs 16 being presented to the channels formed on

or secured to the forme. In this position both balls 18 rest against the stops 19 so the types can be slid from the stick to the forme.

45. It is to be understood that the invention may be applied to existing composing sticks used with grooved type of the character described which may differ in appearance and construction from the example illustrated in the drawings. Furthermore, the shape of the ball race 17 may be varied. For example in place of a curved race, this may be V shape in cross section the V forming an incline. Or, the ball race may take 50 the form of a wedge secured by solder, rivets or like means to the stick.

55. Having thus described my invention what I desire to secure by Letters Patent of the United States is as follows:—

60. 1. In composing sticks for loose types of the character specified means for automatically retaining the types in the stick when the stick is tilted, the said means comprising balls which roll into the path of the 55 type.

2. In composing sticks for loose types of the character specified, an inclined race provided at each end of the stick the races being oppositely opposed, balls fitting into said races, and stops for limiting the inward travel of the balls.

65. 3. A composing stick for loose types of the character specified, balls for retaining the types in the stick the said balls rolling in inclined races and stops for limiting the inward travel of the balls, the said stops being provided with curved hoods so that the balls nest therein.

70. In testimony whereof I have signed my name to this specification.

WILLIAM H. STOREY.
